UNITED STATES PATENT OFFICE.

JACOB THISSEN, OF WARREN, PENNSYLVANIA.

SEWING-MACHINE.

1,149,797.

Specification of Letters Patent. Patented Aug. 10, 1915.

Application filed January 14, 1915. Serial No. 2,215.

To all whom it may concern:

Be it known that I, JACOB THISSEN, a citizen of the United States, residing at Warren, in the county of Warren and State of Pennsylvania, have invented a new and useful 5 Sewing-Machine, of which the following is a specification.

The present invention appertains to sewing machines, and relates more particularly 10 to an over stitch sewing machine adapted for sewing the tips of glove fingers.

One of the objects of the invention, is the provision of an over stitch or glove stitching sewing machine embodying a novel and improved carriage for holding and supporting the glove fingers or other material, so that the same will be properly delivered between the feed disks, for the coöperation therewith of the needle and looper, the carriage having unique means for clamping the tip portions of the glove fingers or other stock applied to the carriage to be sewed.

As a more specific object, this invention aims to provide a series of individual clamping or gripping members carried by the carriage for clamping and holding the glove fingers, in combination with means for holding the clamping members at either closed or open position, and means for simultaneously moving all of the clamping members to open position, so that the fabric may be readily detached from the carriage by a single operation, and in order that the new glove fingers or sections may be applied 35 one at a time to the carriage.

Another object of the invention, is to provide novel means for adjustably supporting the carriage for reciprocatory movement, in order that the carriage may be adjusted to 40 coöperate properly with the feed disks and the needle and looper, when the machine is in operation.

Another object of the present invention is to provide novel means for actuating the 45 carriage and one of the feed disks which coöperates therewith.

It is also within the scope of the invention, to provide a sewing machine embodying the foregoing features, and improved 50 generally in its construction, to enhance the utility thereof.

With the foregoing and other objects in view which will appear as the description proceeds, the invention resides in the combination and arrangement of parts and in 55 the details of construction hereinafter de-

scribed and claimed, it being understood that changes in the precise embodiment of the invention herein disclosed can be made within the scope of what is claimed without departing from the spirit of the invention. 60

The invention is illustrated in its preferred embodiment in the accompanying drawings, wherein—

Figure 1 is a plan view of the sewing machine, parts being broken away, and the top plate and parts carried thereby being removed. Fig. 2 is a front view of the machine, portions being broken away. Fig. 3 is a vertical section taken approximately on the line 3—3 of Fig. 1, and illustrating the actuating means for the carriage, parts being broken away. Fig. 4 is an enlarged fragmental rear view illustrating one end portion of the carriage. Fig. 5 is a cross sectional view of the carriage, taken on the line 5—5 of Fig. 4. Fig. 6 is a longitudinal section of the carriage, taken on the line 6—6 of Fig. 4. Fig. 7 is a sectional detail taken on the line 7—7 of Fig. 3. Fig. 8 is a fragmental detail of the releasing shaft. Fig. 9 is an elevation of one of the supports for the ends of the guide or slide way of the carriage. 75

The sewing machine illustrated is old and well known in its general principles, and the old features will therefore need no special detailed description, other than a mere reference thereto. Thus, the machine embodies a frame or housing 1, through the sides of 80 which a driving shaft 2 is journaled, the same being rotated in any suitable manner. A double cam 3 is carried by the shaft 2 for the coöperation therewith of the looper bar 4, as usual, which carries the looper 5, and the needle bar 6 which is slidable through the front wall of the frame 1 and is operatively connected with the shaft 2 in the customary manner, and carries the needle 7 at its forward or outer end. The looper 5 and 100 needle 7 work over the adjacent portions of a pair of feed disks or wheels 8 and 9, the inner or rear feed disk 8 being carried by the upper end of an upright shaft 11 journaled through the frame at the front thereof. The outer or front feed disk 9 is carried by the upper end of a curved arm or bracket 10, which is fulcrumed to the forward portion of the frame 1, to enable the feed disk 9 to be swung forwardly or outwardly to allow the carriage to be removed. 105

The actuating means which operatively

connects the driving shaft 2 and the feed shaft 11, embodies a horizontal counter shaft 12 journaled through the front and rear walls of the frame 1 below the driving shaft 2, and having a worm wheel 13 secured thereon and intermeshing with a worm 14 secured upon the driving shaft 2. A worm 15 is secured upon the forward protruding end of the counter shaft 12, and intermeshes with a worm wheel 16 secured upon the feed shaft 11. In this manner, the counter shaft 12 is rotated at a slower velocity than the driving shaft 2, and the feed shaft 11 is rotated at a slower velocity than the counter shaft 12, so that the feed shaft 11 will be rotated at a relatively low speed, with respect to the stitch forming mechanism.

In order to support the carriage for reciprocatory movement below the adjacent portions of the feed disks 8 and 9, a chair 17 is mounted upon the forward portion of the frame 1 below the feed disks, and is provided with an upper elongated channelled head 18 within which the intermediate portion of the guide or slide way 19 is secured. The guide or slide way 19 is provided with a longitudinal channel 20 in its top, and is of sufficient length for properly guiding the carriage 21 for rectilinear movement thereon.

The chair 17 is mounted adjustably upon the frame 1, in order that the guide or slide way 19 may be adjusted properly to allow the carriage to coöperate with the needle and looper, and to this end, the lower portion of the chair 17 is provided with a pair of inclined bearing surfaces 22 which seat upon a pair of inclined bearing surfaces 23 formed upon the forward portion of the frame 1, in order that when the chair 17 is adjusted longitudinally, it will be raised or lowered according to the direction in which it is moved. The base of the chair 17 is provided with a pair of slots 24 above the bearing surfaces 23 of the frame, and clamping screws 25 extend through the slots 24 and threadedly engage the frame, in order that when the screws 25 are tightened, they will clamp the chair 17 at its adjusted position, and prevent the chair from swinging or vibrating. As a means for adjusting the chair 17 to a nicety, the frame 1 is provided at the remote ends of the inclined surfaces 23, with upstanding ears 26, through which adjusting screws 27 are threaded to bear against the ends of the chair 17. Thus, when one of the adjusting screws 27 is loosened, the other may be threaded to force the chair 17 in advance thereof, and when both of the screws 27 are tightened, they will bear against the ends of the chair to hold the chair against longitudinal movement. It is evident that by adjusting the screws 27, the chair 17 may be accurately

adjusted for properly supporting the guide or slide way 19 carried by the chair.

As a means for adjustably supporting the ends of the guide or slide way 19, standards 28 are secured upon the table or other base 70 upon which the frame or casing 1 is secured, below the ends of the guide 19, and are preferably formed from bars having their upper and lower ends bent angularly. Adjusting screws 29 are threaded upwardly through 75 the upper end portions of the standards 28 and bear against the bottom of the guide 19 adjacent the ends thereof, in order that the screws 29 may be adjusted for properly supporting the ends of the guide. Locking or 80 binding nuts 30 are preferably threaded upon the screws 29 for binding them at the positions to which they are adjusted, in order that they will not become loosened 85 accidentally.

A support is also provided beyond one end of the guide 19, for supporting the respective end of the carriage 21, when the carriage is moved partially out of the guide 19 when the series or row of glove fingers 90 have nearly passed through the stitching mechanism. To this end, a standard 31, resembling the standard 28, is secured upon the table or other base beyond one end of the guide 19, and a vertical shank 32 is 95 slidable through the upper end portion of the standard 31, and has a pair of clamping or binding nuts 33 threaded thereon to bear against the upper end portion of the standard 31 for holding the shank 32 at various 100 adjusted positions. The upper end of the shank 32 has a fork 34 within which a bearing wheel or roller 35 is journaled, the wheel 35 being supported at such a vertically adjusted position, as to receive the 105 carriage 21 thereon when the carriage is projected sufficiently out of the guide 19 during the completion of the stitching of the material supported by the carriage.

Coming to the detail construction of the 110 carriage 21, the same embodies a bar 36 of suitable length, and set on edge, so that its lower edge portion is slidable within the channel or groove 20 of the guide or slide way 19, and the lower edge portion of the bar 36 is provided at its rear or inner side, with a rack 39, which intermeshes with a spur gear 38 secured upon the feed shaft 11 below the worm wheel 16. Consequently, the carriage 20 is moved longitudinally at 115 the proper speed by the feed shaft 11, it being noted that the feed disk 8 is also carried by the shaft 11, so that the said feed disk and carriage will move at the same relative speed. The spur gear 38 works through a recess or cut away portion 39' of the guide or slide way 19 at the rear of the channel 20.

The carriage embodies means for supporting or holding the glove fingers or other articles to be sewed, and to this end, an 130

elongated horizontal plate 40 has its lower edge portion secured in any suitable manner to the front side of the bar 36, and the upper edge portion of the plate 40 is adapted to receive thereover, the glove fingers or other articles, and is arranged to move between the disks 8 and 9 under the looper 5 and needle 7, so that the material carried by the upper edge of the plate 40 will be stitched over the upper edge of the said plate. The over stitch mechanism and operation is well known, and needs no specific description, and the coöperation of the carriage with the stitch forming mechanism will also be obvious to those versed in the art.

The means for clamping or gripping the glove fingers upon the carriage 21, or against the plate 40 thereof, includes a longitudinal metal cleat 41 secured to the rear or inner side of the plate 40 between the upper and lower edges thereof, and having a longitudinal series of notches or recesses 42, and a lower longitudinal groove 43. An upright clamping lever 44 is fulcrumed within each notch 42 of the cleat 41, each of the levers 44 having a pair of laterally projecting trunnions or lugs 45 intermediate of its ends and projecting from its opposite sides, and the lugs 45 of the levers are seated upwardly within the groove 43 of the cleat 41, to fulcrum the levers to the carriage. The upper arms or ends of the levers 44 which are remote from the bar 36 are in the form of flat jaws 46 terminating slightly below the upper edge of the plate 40, and which are adapted for clamping the glove fingers or other articles 47 against the rear side of the supporting plate 40. The lower arms or ends of the levers 44 are rounded, as at 47', for coöperation with the devices for holding the jaws 46 in either closed or opened position. To this end, the upper edge portion of the bar 36 of the carriage, is provided with a longitudinal series of bores or sockets 48 within the mouth portions of which balls 49 are movable or slideable, coiled wire expansion springs 50 being seated in the sockets 48 under the balls 49 to yieldably raise the same against the lower rounded ends 47' of the levers 44. The lower ends or arms of the levers 44 are adapted to work backwardly and forwardly over the spring pressed balls 49, to positions in rear or in front of the same, whereby the balls 49 will hold the levers 44 at either open or closed position. Thus, when one of the levers 44 is swung from one position to the other, the lower rounded end of the lever 60 will press the spring pressed ball 49 downwardly, and when the lever assumes the new position, the ball 49 will be raised to hold the lever in its new position. It is evident at this point, that the levers 44 are independent or separate, in order that they may

be independently manipulated for clamping the glove fingers or other articles upon the plate 40, in the order that the articles are applied to the carriage. The articles may thus be applied one at a time to the carriage, and clamped thereto as they are applied.

A releasing device is employed whereby all of the levers 44 may be swung to open or released position simultaneously, and to this end, a longitudinal releasing shaft 51 is journaled through suitable bearings 53 carried by the rear side of the plate 40. The releasing shaft 51 is disposed immediately in rear of the lower arms of the levers 44, and is provided at one end with a suitable radial handle 52, whereby the shaft 51 may be rocked or oscillated to swing the levers 44 to open or released position. The shaft 51 is provided with notches or recesses 54 complementing the lower arms of the levers 44, and arranged to receive the same when the levers 44 are swung to closed position, and whereby the adjacent portions of the shaft 51 serve as cams to bear against the lower arms of the levers 44, and swing said lower arms forwardly when the handle 52 is swung properly, so as to swing the levers 44 to open position.

In use, the carriage 21 may be lifted out of the guide or slide way 19, when the arm 95 or bracket 10 is swung forwardly to separate the feed disks 8 and 9, and then, by rocking the shaft 51 properly, the levers 44 will be swung open simultaneously, which will immediately release the articles from the carriage, and enable the new glove fingers or articles to be applied over the upper edge of the plate 40 one at a time, and as the articles are applied to the carriage, the respective levers 44 may be sprung to clamping position for holding the successive articles in place. Then, when the carriage is filled, it may be replaced within the guide 19, for coöperation with the stitching and feeding mechanisms. It is obvious, that as the machine is operated, the carriage will be fed slowly under the stitching mechanism, so that those portions of the glove fingers or other articles 47 above the upper edge of the plate 40, will be stitched together, the present machine being intended particularly for glove stitching purposes.

The other advantages and attributes of the invention are thought to be obvious from the foregoing, taken in connection with the drawings, without further comment being necessary.

It is to be noted that the springs 50 in raising the balls or detent elements 49, will also serve to hold the levers 44 raised, so that their trunnions or pivots 45 will remain within the groove 43 of the cleat 41.

Having thus described the invention, what is claimed as new is:

1. In a sewing machine, a frame, a car-

riage carried by the frame and having a rack, a driving shaft carried by the frame, a counter shaft carried by the frame, a worm secured upon the driving shaft, a worm 5 wheel secured upon the counter shaft and intermeshing with the said worm, a feed shaft, a feed disk carried by the feed shaft and coöperating with the carriage, a spur gear carried by the feed shaft and intermeshing with the said rack, a worm secured 10 upon the counter shaft, and a worm wheel secured upon the feed shaft and intermeshing with the last mentioned worm.

2. In a sewing machine, a frame having 15 an inclined surface, a chair having an inclined surface seating upon the aforesaid inclined surface, a slide way carried by the chair, a carriage movable upon the slide way, and means for adjusting and holding 20 the chair upon the first mentioned inclined surface.

3. In a sewing machine, a frame having a pair of inclined surfaces, a chair having a pair of inclined surfaces seating upon the 25 aforesaid inclined surfaces, a slide way carried by the chair, a carriage movable upon the slide way, the frame having upstanding portions at the remote ends of the inclined surfaces, adjusting screws threaded through 30 the said portions and bearing against the ends of the chair for adjusting it, and means for clamping the chair upon the first mentioned inclined surfaces.

4. A sewing machine carriage having a 35 plate adapted to support articles over its upper edge portion, a series of clamping devices carried by the carriage and coöperable with the plate to clamp the articles thereagainst, the clamping devices being 40 adapted to be moved to clamping and released positions, means for independently holding the clamping devices at either clamping or released position, and means for simultaneously swinging the clamping 45 devices to released position.

5. A sewing machine carriage having a plate adapted to receive articles over its 50 upper edge, a series of clamping devices carried by the carriage and coöperable with the plate to clamp the articles thereagainst, yieldable means for independently holding the clamping devices at either clamping or released positions, and a longitudinal shaft journaled to the carriage and having portions 55 coöperable with the clamping devices for simultaneously moving them to released position.

6. A sewing machine carriage having a plate adapted to receive articles over its upper edge, a series of levers fulcrumed to the carriage and having jaws coöperable with the said plate for clamping the articles thereagainst, yieldable means coöperable 60 with the levers for independently holding them at either open or closed positions, and

a longitudinal shaft journaled to the carriage and having portions coöperable with the levers for simultaneously swinging them to open position.

7. A sewing machine carriage having a 70 plate adapted to receive articles over one edge, clamping levers journaled to the carriage and having jaws coöperable with the said plate to clamp the articles thereagainst, yieldable means carried by the carriage and 75 coöperable with the levers for independently holding them at either open or closed positions, and a longitudinal shaft journaled to the carriage and having recesses for receiving the levers and forming portions coöperable therewith to swing them to open position simultaneously.

8. A sewing machine carriage having a plate adapted to receive articles over its edge, clamping levers fulcrumed intermediate 80 their ends to the carriage, each lever having one arm in the form of a jaw coöperable with the said plate to clamp one of the articles thereagainst, and a spring pressed detent carried by the carriage and 85 coöperable with the other arm of each lever for holding the lever at either open or closed position.

9. A sewing machine carriage having a plate adapted to receive articles over its edge, 90 clamping levers fulcrumed intermediate their ends to the carriage, each lever having one arm in the form of a jaw coöperable with the said plate to clamp one of the articles thereagainst, a spring pressed detent carried by the carriage and coöperable with the other arm of each lever for holding the lever at either open or closed position, and means for simultaneously swinging the levers to open position.

10. A sewing machine carriage having a plate adapted to receive articles over its edge, clamping levers fulcrumed intermediate 100 their ends to the carriage, each lever having one arm in the form of a jaw coöperable with the said plate to clamp one of the articles thereagainst, a spring pressed detent carried by the carriage and coöperable with the other arm of each lever for holding the lever at either open or closed position, and a longitudinal shaft journaled to the carriage 110 and having portions coöperable with the levers for simultaneously swinging them to open position.

11. A sewing machine carriage embodying a bar, a plate secured thereto, and adapted to receive articles over its edge, a cleat secured to the plate, levers fulcrumed to the cleat, those arms of the levers remote from the bar having jaws coöperable with the 120 plate to clamp the articles thereagainst, and yieldable elements carried by the bar and coöperable with the other arms of the levers to hold the levers at either closed or open 125 positions.

12. A sewing machine carriage embodying a bar, a plate secured thereto and adapted to receive articles over its edge, a cleat secured to the plate, levers fulcrumed to the cleat, those arms of the levers remote from the bar having jaws coöperable with the plate to clamp the articles thereagainst, yieldable elements carried by the bar and coöperable with the other arms of the levers to hold the levers at either closed or open positions, and means carried by the carriage for simultaneously swinging the levers to open position. 70

13. A sewing machine carriage embodying a bar, a plate secured thereto and adapted to receive articles over its edge, a cleat secured to the plate, levers fulcrumed to the cleat, those arms of the levers remote from the bar having jaws coöperable with the plate to clamp the articles thereagainst, yieldable elements carried by the bar and coöperable with the other arms of the levers to hold the levers at either closed or open positions, and a longitudinal shaft journaled to the carriage and having portions coöperable with the last mentioned arms of the levers for swinging them to simultaneously swing the levers to open position. 75

14. A sewing machine carriage having a plate adapted to receive articles over its edge, a cleat carried by the carriage and having a series of notches and a longitudinal groove, clamping levers disposed within the said notches and having trunnions intermediate their ends seated in the said groove, one arm of each lever having a jaw coöperable with the said plate for clamping one of the articles thereagainst, and yieldable elements carried by the carriage and coöperable with the other arms of the levers for holding the levers at either open or closed position and for holding the trunnions thereof seated within the said groove. 95

15. A sewing machine carriage having a plate adapted to receive articles over its edge, a cleat carried by the carriage and having a series of notches and a longitudinal groove, clamping levers disposed within the said notches and having trunnions intermediate their ends seated in the said groove, one arm of each lever having a jaw coöperable with the said plate for clamping one of the articles thereagainst, yieldable elements carried by the carriage and coöperable with the other arms of the levers for holding the levers at either open or closed position and for holding the trunnions thereof seated within the said groove, and means for simultaneously swinging the levers to open position. 100

16. A sewing machine carriage embodying a bar and a plate secured thereto and adapted to receive articles over its edge, a cleat secured to the plate and having a series of notches and a longitudinal groove, clamp-

ing levers disposed within the said notches and having trunnions intermediate their ends seated in the said groove, those arms of the levers remote from the bar having jaws coöperable with the said plate for clamping the articles thereagainst, the bar having sockets, spring pressed detents working within the said sockets and coöperating with those arms of the levers adjacent the bar, for holding the levers at either closed or open position. 105

17. A sewing machine carriage embodying a bar and a plate secured thereto and adapted to receive articles over its edge, a cleat secured to the plate and having a series of notches and a longitudinal groove, clamping levers disposed within the said notches and having trunnions intermediate their ends seated in the said groove, those arms of the levers remote from the bar having jaws coöperable with the said plate for clamping the articles thereagainst, the bar having sockets, spring pressed detents working within the said sockets and coöperating with those arms of the levers adjacent the bar for holding the levers at either closed or open position, and a longitudinal shaft journaled to the frame and having portions coöperable with the last mentioned arms of the levers for simultaneously swinging the levers to open position. 90

18. A sewing machine carriage having a plate adapted to receive articles over its edge, a series of levers fulcrumed intermediate their ends to the carriage, one arm of each lever having a jaw coöperable with the plate to clamp one of the articles thereagainst, the other arm of each lever having a rounded end, the carriage having sockets, balls working within the mouths of the said sockets, and coöperable with the rounded ends of the levers, and springs seated within the sockets for pressing the balls into coöperative relation with the rounded ends of the levers, whereby the levers will be held at either open or closed positions. 105

19. A sewing machine carriage having a plate adapted to receive articles over its edge, a series of levers fulcrumed intermediate their ends to the carriage, one arm of each lever having a jaw coöperable with the plate to clamp one of the articles thereagainst, the other arm of each lever having a rounded end, the carriage having sockets, balls working within the mouths of the said sockets, and coöperable with the rounded ends of the levers, springs seated within the sockets for pressing the balls into coöperative relation with the rounded ends of the levers, whereby the levers will be held at either open or closed position, and means for simultaneously swinging the levers to open position. 115

20. A sewing machine carriage embodying a bar and a plate secured thereto, and

adapted to receive articles over its edge, a cleat secured to the plate and having a series of notches and a longitudinal groove, clamping levers disposed within the said notches 5 and having trunnions intermediate their ends seated in the said groove, those arms of the levers remote from the bar having jaws coöperating with the said plate for clamp- ends seated in the said groove, those arms of 10 the levers adjacent the bar having rounded ends, the bar having sockets, balls working within the mouths of the said sockets and co- operable with the rounded end of the levers, and springs seated within the said sockets 15 for holding the balls against the rounded ends of the levers for holding the levers at either open or closed positions.

21. A sewing machine carriage embodying a bar and a plate secured thereto, and 20 adapted to receive articles over its edge, a cleat secured to the plate and having a series of notches, and a longitudinal groove, clamping levers disposed within the said notches and having trunnions intermediate

their ends seated in the said groove, those 25 arms of the levers remote from the bar having jaws coöperable with the said plate for clamping the articles thereagainst, those arms of the levers adjacent the bar having rounded ends, the bar having sockets, balls 30 working within the mouths of the said sockets and coöperable with the rounded ends of the levers, springs seated within the said sockets for holding the balls against the rounded ends of the levers for holding the levers at either open or closed positions, and a longitudinal shaft journaled to the carriage and having portions coöperable with the last mentioned arms of the levers 35 for swinging the levers simultaneously to 40 open position.

In testimony that I claim the foregoing as my own, I have hereto affixed my signature in the presence of two witnesses.

JACOB THISSEN.
